UNITED STATES PATENT OFFICE

ROBERT GEORGE FARGHER, LESLIE DOUGLAS GALLOWAY, AND MAURICE ERNEST PROBERT, OF MANCHESTER, ENGLAND, ASSIGNEES TO THE BRITISH COTTON INDUSTRY RESEARCH ASSOCIATION, OF DIDSBURY, ENGLAND, A BRITISH ASSOCIATION

PROOFING OR LIKE TREATMENT OF MATERIALS TO PROTECT THEM FROM MILDEW AND OTHER FUNGOID GROWTHS

No Drawing. Application filed October 18, 1929, Serial No. 400,727, and in Great Britain October 18, 1928.

This invention relates to a treatment by which goods of all descriptions, but especially textile materials, may be protected from the attack of mildew and other fungoid growths or may be given increased power of resistance to such attack.

According to our invention the goods, which may be yarns or fabrics composed of textile material or may be paper, leather, rubber, timber, adhesives, etc., are treated with an arylamide of a salicylic acid, preferably in the form of its alkali salt. In particular we find that salicylic anilide and alkoxyanilide are very effective agents for this purpose. Arylamides of substituted salicylic acids, and arylamides other than the anilide or o-anisidine are also found to be suitable though to a smaller degree; amongst these may be mentioned 5-chlorosalicylanilide, β -resorcylic anilide, salicylic o-toluidide, and many others.

The arylamide may be applied to the goods in any convenient manner, and to the finished goods or at any convenient stage in their manufacture. For example the goods to be treated may be sprayed or painted with or immersed in a solution of the alkali salt of the salicylic arylamide; or the latter may be added during the sizing, mordanding, dyeing, finishing or other operative treatment of the goods, or may be incorporated into the mass, solution etc. constituting one stage in the manufacture of the goods.

For the proofing of cotton or other yarns or fabrics against mildew etc. we may, according to one form of our invention, introduce into the sizing bath a solution of the arylamide in aqueous caustic soda, or an aqueous solution of the sodium salt of the arylamide. More usually, the antiseptic will be applied in the form of a suspension or partial solution in water. In all cases the amount of arylamide taken up by the goods may be from 0.01 to 0.1 per cent. of the weight of the goods; larger or smaller proportions may be applied, if desired, without departing from our invention.

What we claim and desire to secure by Letters Patent:—

1. A sizing bath for cotton yarns and fabrics comprising in aqueous solution an alkali

salt of an arylamide of a salicylic acid selected from a class consisting of a salicylic anilide, salicylic alkoxyanilide, 5-chlorosalicylanilide, β -resorcylic anilide and salicylic o-toluidide.

2. A sizing bath for cotton yarns and fabrics comprising in aqueous solution an alkali salt of an arylamide of a salicylic acid selected from a class consisting of salicylic anilide and alkoxyanilide.

3. A sizing bath for cotton yarns and fabrics comprising the sodium salt of salicylanilide in aqueous solution.

4. As a new article of manufacture, a material usually subject to the attack of fungus impregnated with a mildew-proofing concentration of an alkali salt of an arylamide of a salicylic acid selected from a class consisting of salicylic anilide, salicylic alkoxyanilide, 5-chlorosalicylanilide, β -resorcylic anilide and salicylic o-toluidide.

5. As a new article of manufacture, a material usually subject to the attack of fungus impregnated with a mildew-proofing concentration of an arylamide of a salicylic acid selected from a class consisting of salicylic anilide and alkoxyanilide.

6. As a new article of manufacture, a material usually subject to the attack of fungus impregnated with a mildew-proofing concentration of an arylamide of a salicylic acid selected from a class consisting of salicylic anilide, salicylic alkoxyanilide, 5-chlorosalicylanilide, β -resorcylic anilide and salicylic o-toluidide.

7. As a new article of manufacture, a material usually subject to the attack of fungus impregnated with a mildew-proofing concentration of salicylanilide.

8. As a new article of manufacture, a material usually subject to the attack of fungus impregnated with from 0.01 to 0.1 per cent by weight of said material of an arylamide of a salicylic acid selected from a class consisting of salicylic anilide, salicylic alkoxyanilide, 5-chloro-salicylanilide, β -resorcylic anilide and salicylic o-toluidide.

9. As a new article of manufacture, a material usually subject to the attack of fungus

impregnated with from 0.01 to 0.1 per cent
by weight of said material of salicylanilide.

In testimony whereof we affix our signatures.

5

ROBERT GEORGE FARGHER.
LESLIE DOUGLAS GALLOWAY.
MAURICE ERNEST PROBERT.
